UNITED STATES PATENT OFFICE.

ARTHUR G. SMITH AND FRANK R. BATES, OF SEATTLE, WASHINGTON.

SHEET SUPPORTING AND CARRYING CAR.

Application filed November 8, 1923. Serial No. 673,599.

To all whom it may concern:

Be it known that we, ARTHUR G. SMITH and FRANK R. BATES, citizens of the United States of America, and residents of the city 5 of Seattle, in the county of King and State of Washington, have invented certain new and useful Improvements in Sheet Supporting and Carrying Cars, of which the following is a specification.

10 Our invention relates to devices designed for carrying and supporting sheets such as plaster-wall board and the like during the course of manufacture.

15 The object of our invention is to provide a device in which a series of sheets of plaster wall board or other analogous sheet material may be inserted and held in suspended condition, whether for the purpose of transporting or of drying. The device 20 consists essentially of a trolley or car adapted to run upon tracks, preferably overhead, which trolley contains a series of frictional grips or clamps adapted to engage and hold the sheet at or near its upper edge and carry 25 this sheet suspended.

Our invention also consists of the novel means for gripping and holding the sheets.

In the accompanying drawings we have shown our device in the form of construction 30 in which we prefer to use the same.

Figure 1 is a side view showing a section of the supporting trackway with two cars or trolleys thereon and a long sheet supported by the same.

35 Figure 2 is an end view of one of these trolleys or cars showing a portion of the wheel-carrying parts in section.

Figure 3 is a view of the clamping face of one of the arms, that is the face against 40 which the clamping dog operates.

In the manufacture of the particular product for which this was originally designed, namely, plaster-wall board, the wall board is made and maintained in a horizontal plane until it has set sufficiently so 45 that it may be handled. Such sheets, while they may be handled so as to be removed from the carrying surface, are only partially set, and therefore must be maintained in such position and under such conditions that 50 they will not be seriously deformed until they have become entirely set or cured. In the process of manufacturing such boards where the present apparatus is employed, 55 the boards are then placed in the clamping devices of the cars and suspended from their

upper edges, in which condition they are maintained during the transportation and drying or curing operations.

The trolleys or cars as we prefer to construct them are provided with four pairs of wheels, the same being grouped at the four corners of the frame. These wheels 1, as indicated are designed for engaging opposite edges of the top surface of a flanged rail 10. It is evident that a single wheel 60 may be employed instead of the double wheels, if the trackway be designed to properly coat therewith. The particular type of construction of the wheels and the rails 65 is not an essential part of our invention. The particular type illustrated may be replaced by any other convenient type which is found applicable.

The frame 11 in which the wheels are 70 journaled is preferably given a connection with the main frame of the car, such that it may have slight automatic adjustment about a vertical axis. This is done by making the frame 11 in two side pieces, which 75 are bolted together, and in providing these pieces with recesses adapted to receive the head 20 carried on the end of a short arm which connects it with the cross bars 2 of the car. The main frame of the car consists of 80 two of the cross bars 2 connected by two angle bars or other connecting bars 21. However, the exact construction of the main frame is also immaterial.

Each of the cross bars 2 of the frame is 85 provided with a series of sheet gripping and holding clamps. These devices are of such nature as to grasp and frictionally hold the sheets of plaster-wall board without perforating or marring them. Each of the 90 clamping devices consists of two arms having opposed faces, of which one has an inclined surface coacting with a gravity dog 95 to grip the side of the sheet.

In Figure 2 three sheets A are shown as 100 in place in the device. The arms 3 are all essentially alike, excepting the arm at one end of the series which has been designated as the arm 30. Each of the arms 3 has one perpendicular surface, as 31, against which one side of the sheet A is placed. The other face, 32, is provided with a projection having an inclined face 33, the same being inclined towards the adjacent arm 3, so that the space between this inclined face and the 105 opposed face of the adjacent arm is reduced towards the lower end thereof. Placed be-

tween each pair of adjacent arms is the gravity dog 4, which in the construction of car herein illustrated consists of a short section of pipe, the same being of such a length 5 as to reach from one of the cross bars 2 to the other and to act as a common dog for each of these pairs of gripping devices.

To facilitate entering the upper edge of the sheet A between the bars 3, a projection 10 34 is employed, which extends from the outer face of the incline 33 downwardly and back to the arm 3. This is widened towards its lower side as indicated in Figure 3, so as to form a considerable surface in its lower 15 part, against which the edge of the sheet may impinge if it is not exactly positioned to pass between the bars.

The gravity dogs 4 are normally, or before the placing of the sheets in position, 20 resting as shown at the right hand portion of Figure 2. In this position they bear against the face 31 and are supported at the opposite side by bearing upon a slight projection or ledge 35 placed at the bottom of 25 the inclined surface 33. The purpose of the slight projection 35 is to prevent the possibility of the dog 4 becoming wedged between the two surfaces 31 and 32 so that it will not be readily displaced by the edge of the 30 sheet as it is inserted. When so supported at one side by the corner 35, no wedging effect can occur and the gravity dog will be displaced upwardly by the edge of the sheet 35 when it is inserted. The dog will then be inserted between one face of the sheet A and the inclined surface 33, so that when the weight of the sheet acts downwardly upon the dog to wedge it in position and thereby 40 securely grip the sheet and support its weight.

We have found that the action of this dog is more effective and reliable if a layer of some compressible or friction producing material be inserted between the dog 4 and the 45 inclined surface 33. As a convenient way of doing this we have employed small pieces of paper, the same being of the thickness and type employed in manufacturing the plaster-wall board. Any good frictional 50 surface might answer for this purpose. Without employing such a frictional member we have found that occasionally the weight of the sheet, acting upon the circular dog 4, will cause it to turn with a sliding 55 movement over the face of the incline 33, and thus permit the sheet to drop. This of course might be prevented by roughening the surface of the dog and of the incline 33, but this roughening of the surface of the dog 60 would tend to mar the face of the sheet A.

In handling long sheets of plaster-wall board two such cars or trolleys should be employed, these being located towards the ends of the sheet. If the sheet be of unusual 65 length it may be necessary to employ more

than two such cars. At the same time it is possible to employ these cars separately where the sheets being made are short, in which case a single car is sufficient. Each of these cars or pairs of cars, as the case 70 may be, supports as many sheets as there are spaces between the arms 3. The series of sheets so supported are transported upon the overhead rails 10 and moved about the factory as may be desired. They are permitted to remain so suspended by the gripping devices of the cars during the process of curing or drying.

We have found that the above device is one which makes handling of the sheets easy 80 and rapid and also contributes to ease of transportation. By suspending the sheets from one edge it tends to keep the sheets in true condition without warping and at the same time, by permitting free circulation of air between the sheets, contributes materially to the efficient and quick drying of the sheets.

While we have described our invention as applied to the handling of plaster-wall board, it is evident that it may be applied to the handling of any other sheet material. Therefore wherever in the specification and claims the term plaster-wall board is used it is to be understood that this is intended only 95 as illustrative of a type of sheet material for the use with which our invention is designed and not as limiting it to that particular material.

What we claim as our invention is:

1. An automatic holding means for plaster-wall board and like sheet material comprising two depending arms having opposed gripping faces, the gripping face of one arm being vertical and the complementary face of the other arm converging downwardly toward the said vertical face and then further downwardly diverging from said vertical face, and a gravity locking dog loosely supported between the arms above 105 and the apex formed by said inclined faces.

2. An automatic holding means for plaster-wall board and like sheet material comprising two depending arms having opposed faces, said face of one arm being 110 downwardly inclined toward the other arm and having a slight projecting ledge at the bottom of the incline, and a gravity dog of circular outline of a size to be supported between said ledge and the opposing face of the other arm when the device is empty.

3. An automatic holding means for plaster-wall board and like sheet material comprising two aligned pairs of depending arms, the arms of each pair having separated opposing faces of which the face of one arm has an inclined surface downwardly converging towards the other arm and a gravity dog consisting of a bar extending between the two pairs of arms and 125 130

normally supported loosely between the base of the inclines of one arm of each pair and the opposed face of the other arm of each pair.

5. A suspending and transporting device for a series of plaster-wall boards and like sheets comprising a car having a series of parallel disposed sheet holding means each comprising two alined pairs of arms, and a bar forming a gravity dog and extending between the two pairs of arms.

10. A suspending and transporting device for a series of plaster-wall boards and like sheets comprising a car having a series of parallel disposed sheet holding means each comprising two alined pairs of arms, a bar forming a gravity dog and extending between the two pairs of arms, each arm except the outermost of each series being 15 common for adjacent pairs.

15. A sheet suspending means comprising a series of depending arms connected together in alinement in a direction transverse of the sheets to be held, the opposed 20 faces of adjacent arms being downwardly inclined towards each other, and a gravity dog supported between said inclined surfaces.

25. A friction gripping device for wall

boards and like material comprising two 30 frame members separated to permit insertion of the boards between them, one of said frame members having an inclined face downwardly converging toward the other member, a layer of yielding and friction-increasing material covering said inclined face, and a cylindrical gravity dog supported between said inclined face and the other member.

35. A friction gripping device for plaster-wall board and like sheet material comprising two members having opposed faces between which an edge of the board may be inserted, one of said faces being substantially vertical and the other inclined downwardly toward said vertical face, said inclined face having a slightly projecting ledge at the lower edge of the incline, and a cylindrical gravity dog adapted to be supported by said ledge and the face of the 40 opposite member and to be displaced upwardly and away from the vertical face by insertion of the sheet to be held thereby.

45. Signed at Seattle, King County, Washington, this 30th day of October, 1923.

FRANK R. BATES.
ARTHUR G. SMITH.
